SEPARATING MACHINE

Frank H. Jacobson, Minneapolis, Minn.

Application March 27, 1940, Serial No. 326,218

14 Claims. (Cl. 209—228)

This invention relates to a separating or cleaning device. Certain food and other products, such as cereals, which have been passed through machinery of various kinds, accumulate some small metallic material and often contain very light dust-like material which it is desired to separate therefrom.

It is an object of this invention to provide a device which will separate metallic particles from a body of material and one which preferably will be continuous and automatic in operation.

It is another object of the invention to provide a separating device comprising a rotatable member having a magnet in a part of its periphery over which the material is passed, together with means for periodically de-energizing said magnet and rotating said member to free material therefrom.

It is another object of the invention to provide a device for effecting an air separation of the very light non-magnetic particles from the material, the heavier particles then being passed over a magnetic means for separating magnetic material therefrom.

It is more specifically an object of the invention to provide a separating device comprising a rotatable drum having a magnet in a portion of its periphery with means for holding said drum stationary with said magnet in operative position, means for rendering inoperative said first mentioned means, together with means for then rotating said drum, de-energizing said magnet and removing material from said drum and magnet.

It is still further an object of the invention to provide a separating device comprising a rotatable drum having a magnet in a portion of its periphery with coils for said magnet within said drum and means for passing a current of air through said drum to cool said coils.

These and other objects and advantages of the invention will be fully set forth in the following description made in connection with the accompanying drawings in which like reference characters refer to similar parts throughout the several views and in which:

Fig. 1 is a vertical section taken substantially on line 1—1 of Fig. 3 as indicated by the arrow;

Fig. 2 is a wiring diagram for the device;

Fig. 3 is a view partly in end elevation and partly in vertical section taken substantially on line 3—3 of Fig. 1 as indicated by the arrow also showing the upper casing of the machine;

Fig. 4 is a view in vertical section taken sub-

stantially on line 4—4 of Fig. 1 also showing the upper casing of the machine;

Fig. 5 is a view partly in end elevation and partly in vertical section taken on line 5—5 of Fig. 1 as indicated by the arrows;

Fig. 6 is a view in end elevation of a stop mechanism used; and

Fig. 7 is a top plan view of the mechanism shown in Fig. 6.

Referring to the drawings, a machine is shown comprising a casing or frame designated generally as 10, the same having a base plate portion 10a. End plates 10b extend vertically at each end of said frame from which project outwardly cylindrical portions 10c. Vertical ribs 10d and 10e extend at the center and sides of the frame at each end and horizontal ribs 10f extend outwardly from the cylindrical portion 10c to the vertical ribs 10e. The casing is divided 10 along a horizontal diameter of the portions 10c and there is an upper portion 10g comprising the upper half of portions 10c, horizontal ribs 10h engaging ribs 10f and a substantially semi-cylindrical portion 10i. Portion 10i has an upwardly projecting housing portion 10j adapted to enclose certain driving parts. An outer housing 11 extends upwardly above ribs 10f, the same being substantially rectangular in horizontal cross section but having at one upper side a vertically projecting chute 12 having an inclined bottom portion 12a, said chute being open at its bottom to communicate with the chamber within housing 11. Housing 11 is shown as hinged at one side by hinges 13 to the lower portion of casing 10 so that the same can be swung or tilted.

A drum designated generally as 14 is provided, the same having end members 14a each provided with an outwardly projecting cylindrical flange 14b and a central hub 14c, flange 14b being connected to hub 14c by radial arms 14d. Hubs 14c have secured therein shafts 15 and 16 respectively which are journaled in bearings 17 shown as of the ball type and held in place at their inner sides by plates 18 and at their outer sides by nuts 19 threaded on reduced portions of shafts 15 and 16 respectively. The bearings 17 are carried in members or blocks 20 secured to casing 10. The drum 14 has mounted therein a magnet frame designated generally as 21, the same having side plates 21a and an end plate 21b. Pole pieces 22 extend lengthwise of drum 14 and have wound thereon the magnet coils 23 which extend substantially the full length of drum 14. The magnet portion 24 is secured to the outer ends 50 of pole pieces 22 and side members 21a, the same

having its outer surface lying substantially in the periphery of drum 14 and a casing 14e of rather thin material extends about the inner portions of flanges 14b from one side of magnet 24 to the other side thereof. The end plate 21b as shown is made rather heavy and of considerable weight to act as a counterbalance for drum 14 as the coils 23 are off center or eccentric of said drum. Magnet 24 is shown as having recesses in the face thereof with flat sides in angular relation. The drum 14 is adapted to be driven and for this purpose rollers 26 are provided adapted to engage the outer side of each flange 14b, said rollers being secured to a shaft 27 having its ends journaled in the ends of frame portions 10j, said shaft projecting beyond said frame portion 20 said shaft having secured thereto at one end a gear 28 with which meshes a pinion 29. Pinion 29 is secured to a shaft 30 also having its ends journaled in the end portions of frame portions 10j, said shaft 30 having secured thereto at one end and having a pulley 31 secured thereto shown as having a V-shaped groove therein. The drum flanges 14b each have a recess 14f formed therein for a portion of its periphery, the bottom of which is spaced from the periphery of roller 26. As shown in Fig. 4 there is a slot 10m providing for adjustment of shaft 27 and rollers 26 as the flanges 14b wear. Shaft 30 also has a small pulley 32 secured thereto within one of the portions 10j which is in line with a pulley 33 journaled on shaft 15. A fan 34 is secured to pulley 33 arranged to direct a current of air inwardly through drum 14. It will be noted that pulley 33 is disposed between the end of hub 14c and the end of plate 18. A belt 36 passes over pulley 32 and over another pulley 37 journaled on a stud 38 secured in one end of frame 10. Belt 36 as shown in Fig. 5 runs along and engages one side of pulley 33 so that the latter is driven.

A switch 40 illustrated as of the mercury tube type is secured to one end of drum 14 and is included in the circuit of the magnet coils 23. When the magnet 24 is in operative position as shown in Fig. 4 the contacts 40a in switch 40 will be closed by the mercury therein. When the drum revolves so that the mercury runs into the other end of the tube, contacts 40 will be separated and current will be cut off from the coils 23 so that magnet 24 will be de-energized. A ring supporting member 41 of insulating material is secured to the outer end of shaft 16, being engaged by a plate 41c and slip rings 41a and 41b are carried on member 41 at each side of an annular rib thereon. Rings 41a and 41b are respectively engaged by a pair of brushes 42, the outer one of which is shown in Fig. 3. Shaft 16 has a central bore 16a through which conductors from coils 23 pass, one conductor being connected to slip ring 41a in any suitable manner and the other being connected to one contact of switch 40. The other contact of switch 40 is connected by a suitable conductor to the other ring 41b in any convenient and suitable manner. Drum 14 has on one of its flanges 14b a stop lug 14g arranged to be engaged by a stop pin 43. Pin 43 forms the core of a solenoid 44 having a coil surrounding said pin. A coiled compression spring 43b underlies plunger 43 normally urging the same to its outward position. Said solenoid 44 is pivoted for swinging movement on a stud 45 secured to a bracket 46 in turn carried by and secured to base plate 10a by bolts 46a. Pin 43 has a recess 43a in its end into which lug 14g moves when pin 43 is in stop position, said recess forming a flat surface for engagement of lug 14g. The solenoid or magnet 44 is normally

urged to swing to the right as seen in Figs. 3 and 6 by a tensile coiled spring 47 secured thereto by a stud 48 and secured at its other end to bracket 46 by a stud 49. Stud 48 projects outwardly as a pin and is adapted to engage a yoke or substantially V-shaped member 50 pivoted to bracket 46 at its bight end by a stud 51. A headed stud 52 projects from one side of member 50 and is engaged by a plate spring 53 extending upwardly from 10 and secured to bracket 46 by a screw 54. A magnet coil 55 is mounted on frame 46 by a headed screw 56 and has a pole piece 57 extending across its lower end and having side portions disposed vertically at either side thereof, the tops of which are in one plane and adapted to be engaged by one side of member 59. Member 59 carries a pair of switches 58 and 59 shown as of the mercury tube type, the same having contacts 58a and 59a respectively. A timer device or clock is used which turns a disk 60 having therein a plurality of notches 60a equally spaced circumferentially thereof. The number of these notches may be varied and disks having various numbers of notches may be used. In the embodiment of the invention illustrated four notches are shown. In one common form of the invention disk 60 is driven from the hour shaft of the clock. A pawl 61 pivoted at 62 is resiliently urged against the periphery of disk 60 and a switch 63 is carried by pawl 61. Switch 63 is of the mercury tube type and has contacts 63a. When pawl 61 is riding on the periphery of disk 60 switch 63 is in the position shown so that contacts 63a are separated. When pawl 61 drops into one of the notches 60a tube 63 moves therewith and into position for the mercury to connect contacts 63a. Conductors are shown for the parts in Figs. 6 and 7 including a line conductor 65 which extends to one of the contacts 63a. Another line conductor 66 extends to one end of the winding of solenoid or magnet coil 44. A conductor 67 extends from the other contact 63a to one contact 59a and a conductor 68 extends from said contact 59a to one of the contacts 58a. A conductor 69 extends from the other contact 58a to the other end of the winding of solenoid or magnet coil 44. A conductor 70 extends from the other contact 59a to one end of the winding of magnet coil 55. Another conductor 71 extends from the other end of the winding of magnet coil 55 to line conductor 66.

The material is discharged into the top of casing 11 at the opening 11a. The material engages a slide 75 pivoted at 76 and which can be moved to different positions about its pivot. The material engages another slide 77 pivoted at 78 so as to be adjusted about said pivot and an extension slide 79 is secured to slide 77 and movable longitudinally thereof to different positions. Below slides 75 and 77 is a slide 80 movable about a pivot 81 and having an extension slide 82 secured thereto and movable longitudinally thereof. Beneath slide 82 is another slide 83 which inclines downwardly toward drum 14 to a point at the upper end of magnet 24. A slide 84 is pivoted at 85 adjacent one side of casing 11 and inclines downwardly toward slide 83, the same having an auxiliary extension slide 86 movable downwardly toward and from magnet 24. Slide 84 is disposed just below the inclined bottom 12a of chute 12. It will be seen that chute 12 extends upwardly having one side disposed substantially over the end of slide 82 as shown.

Below drum 14 is disposed a slide or deflecting plate 88 pivoted at 89, the same terminating adjacent the top of a receptacle or trough 90.

Trough 90 has a vertical partition 90a therein and a plate 91 extends upwardly in an inclined direction therefrom to a point adjacent a pivot 92 which carries a plate 93. Plate 93 has one or more arms 94 projecting therefrom to the end of each of which is connected a coiled tensile spring 95 having its other end secured to casing 10 at 96. The member 93 will have a member 93a of some soft material, such as lamb's wool, secured along its free edge which will be in engagement with casing 14e. Receptacle 99 is slidably outwardly at one side of casing 10, the same having an end plate 90b engaging the front of casing 10 and base plate 10a and having a handle 90c.

In Fig. 2 a wiring diagram for the machine is shown comprising line conductors 100, 101 and 102 for alternating current. A switch 103 has contacts for engaging said line conductors and conductors 104, 105 and 106 extend to a motor 107 which will have a suitable pulley on the driving shaft thereof from which a belt will pass to pulley 31. Conductors 108 and 109 are shown constituting line conductors for direct current and a switch 110 has contacts for connecting to conductors 108 and 109. A switch 111 is provided having movable contacts 111a adapted to engage respectively with contacts 111b having conductors connected respectively to the contacts of switch 110. A magnet 112 is provided for controlling switch 111, the same being energized by conductors 113 connected in turn by conductors 114 and 115 to two contacts of switch 103. Conductors 114 and 115 extend to the timer disk 60 which is adapted to close the switch 63. A pair of conductors 118 and 119 extend from the contacts 111a of switch 111 and are connected to the brushes 42 respectively which engage rings 41a and 41b respectively. A conductor 120 extends from one ring 41b to one contact of switch 40, the other contact of which is connected to a conductor 121 which extends to one end of one of the magnet coils 23, which coil is connected at its other end to one end of the other magnet coil 23. The opposite end of the latter coil is connected by conductor 122 to the other ring 41a. Conductors 65 and 66 extend from conductors 118 and 119 respectively, conductor 65 being connected to one terminal of switch 63. Conductor 66 extends to one end of the winding of solenoid or magnet coil 44. A conductor 67 extends from the terminal or contact of switch 63 and is connected to a movable contact 72 of a double pole switch having contacts 72a with either of which contact 72 is adapted to engage. One of the contacts 72a is connected by conductor 70 to one end of the winding of magnet coil 55. The other end of the winding of magnet coil 55 is connected by a conductor 71 which extends to and is connected to conductor 66. The other contact 72a is connected by a conductor 69 to the other end of the winding of solenoid or magnet coil 44.

In operation, the material to be separated, such as a cereal food, will be delivered into opening 11a and will slide down between slides 75 and slides 77 and 79. These can be adjusted to give the desired opening therebetween to give the proper feed of material. A current of air will be directed upwardly in housing 12 by a suitable fan (not shown) and the material passing downwardly over the end of slide 79 will be engaged by this current of air. The air will pass through the stream of material and only the very heavy particles which it is desired to eliminate will continue down on slides 82 and 80 and be discharged therefrom. This material will drop into the front

of drawer or receptacle 90 along the side of casing 11 and the side of casing 10. Most of the material will be carried up over the top of slide 82 by the air and will drop down between slides 83 and 84. Only the very lightest particles or dust which it is desired to separate out will pass upwardly in housing 12 with the current of air. The main body of material thus falls between and onto slides 83 and 84 and is directed downwardly at the upper portion of magnet 24. It will be seen that the extension slides 79 can be moved, as stated, to regulate the space through which the air passing through the stream of material must flow. The velocity or force of the air current can thus be regulated. Extension slide 86 can also be moved toward and from drum 24 to regulate the size of the stream of material passing over the drum and magnet. The magnet is in operative position as shown in Fig. 4 and in this position will be energized. The material thus passes down along and over magnet 24 and any small metallic particles will be attracted by and separated out by the magnet. There are usually fine particles in the nature of filings which accumulate from the machinery through which the material has passed. Should there be any larger metallic particles these will also be intercepted and separated by magnet 24. The sharp ridge portions on the magnet giving a sort of saw-tooth effect are provided to give an increase or concentration of flux. As the particles are thus attracted by the magnet and the material continues to flow the particles so attracted will be moved into the recesses on the face of the magnet. The particles thus accumulate in these recesses and are not thus easily swept off of the magnet. The material after passing over the magnet drops down the side of casing 11 and the side of casing 10 and will be discharged through said casing into any suitable receptacle.

Pulley 31 is constantly driven by motor 107 so that belt 36 is constantly driven. Fan 34 is thus driven and a current of air is forced through drum 14, lengthwise thereof, which current acts to keep the magnet coils 23 cool. While the magnet 24 is in its operative position drum 14 is held stationary by stop 43 engaging stop lug 14g. At intervals determined by the timer disk 60 pawl 61 will drop into one of the notches 60a, which as explained, will act to close switch 63. It is pointed out that switch 111 and magnet 112 shown in Fig. 2 are provided so that the direct current to coils 23 and other parts will not be turned on unless the alternating current switch 103 is closed. When the switch 103 is closed magnet 112 is energized through conductors 113 and 114 connected to the line conductors 100 and 101 and switch 111 is moved to closed position. With the magnet in operative position as shown in Fig. 4, switch 40 as already explained is closed. When switch 63 is closed by operation of the timer disk, current is supplied through conductor 66 to one end of the winding of magnet coil 44. Current simultaneously flows through conductor 65, through switch 63, through conductor 67 to conductor 68, through switch 58 which is in closed position as shown in Figs. 3 and 6, then through conductor 69 to the other end of the winding of coil 44. Solenoid or magnet coil 44 is now energized and plunger 43 is moved downwardly into said coil, thus moving out of engagement with lug 14g and releasing drum 14. Shaft 30 is continuously driven and through gears 29 and 28 drives the rollers 26. As shown in Fig. 3 when the magnet 24 is in

operative position the rollers 26 are in line with one end of recesses 14f so that they have no driving effect upon drum 14. As soon as the drum is released by plunger 43 the drum moves in a clockwise direction due to the weight of magnet 24 and coils 23 and the flanges 14b are brought into driving relation to rollers 26. Rollers 26 now engage the flanges 14b and drum 14 is rotated clockwise. As the drum moves around past member 93 and member 93a the material on the magnet and any material which may be on the drum adjacent the magnet is removed therefrom by member 93a and this material drops between the plates 88 and 91 into the drawer 90. When switch 40 moves upward to a position adjacent the top of the drum the mercury therein disconnects the contacts 40a and the circuit through the coils 23 is broken. When magnet 24, therefore, comes to a position between plates 88 and 91 it is de-energized and the material can drop therefrom. Any other material as stated is removed by member 93a. As soon as plunger 43 is withdrawn from lug 14g said plunger with coil 44 is swung downwardly or toward the right as shown in Figs. 3 and 6 by spring 47. The end of plunger 43 thus clears lug 14g which moves past plunger 43. As coil 44 swings downwardly pin 43 engages member 50 and swings the same clockwise about its pivot bolt 51. This swinging movement of member 50 causes opening of the contacts 58a and closing of contacts 59a. The opening of contacts 58a breaks the circuit through coil 46 so that the coil is de-energized and plunger 43 is moved outwardly by its spring. Plunger 44 is thus again in position to be engaged by lug 14g as drum 14 completes a revolution. When contacts 59a of switch 59 are closed by the mercury in said switch a circuit is closed through magnet 55 which may be traced from line conductor 65 through switch 63, conductor 67, switch 59, conductor 70, through the coil of magnet 55, conductor 71 back to line conductor 66. Conductors 65 and 66 as shown in the wiring diagram in Fig. 2 are connected in the direct current line. Magnet 55 is thus energized and member 50 which acts as an armature is held in the position to which it was swung by pin 43 by magnet 51. When the drum 14 completes a revolution lug 14g engages plunger 43 and the drum is again stopped in the position shown in Fig. 3, the magnet 24 is energized by the circuit again being closed through magnet coils 23 by switch 40. The timer disk 60 continues to rotate and pawl 61 is soon moved to position to cause the contacts in switch 63 to be separated and when this occurs the circuit through magnet 55 is broken and said magnet is de-energized. When this happens the leaf spring 53 acting on pin 52 swings member 50 back to the position shown in Fig. 6 and the parts are again in normal position with magnet 24 energized. With the magnet in normal position it will again be noted that driving rollers 26 are opposite one end of the recesses 14f and are thus out of driving engagement with the drum. The action of the two mercury tube switches 58 and 59 is quite similar to that of a double throw double contact switch and such a switch is illustrated as 72, 72a in Fig. 2 instead of showing the two switches 58 and 59.

From the above description it will be seen that I have produced a comparatively simple and very efficient separating device. The machine acts automatically to separate the metallic particles

and to be cleaned of these separated particles. The very heavy and very light non-magnetic particles are also separated from the main body of material treated. By having the magnet only at a portion of the periphery of the drum the mechanism or flux can be highly concentrated at this point and a more certain separation made than where the whole surface of a drum is composed of magnetic portions. Thus by having a portion of the periphery magnetic and periodically rotating the drum to clean the same a more desirable action is secured. The machine has been amply demonstrated in actual practice, is being commercially made, and has been very successful.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A separating device having in combination, a revoluble member having a portion of its periphery formed as a magnet, a stop engaging said member to hold the same stationary, means for rotating said member, a magnet for withdrawing said stop, a circuit for energizing said magnet and a time controlled switch for periodically closing said circuit and withdrawing said stop to permit rotation of said member.

2. A separating device having in combination, a drum having a magnet in a portion of its periphery, a stop, means on said drum engageable with said stop, a magnet coil for moving said stop out of engagement with said means, means for swinging said coil and stop and breaking the circuit of said magnet coil so that said stop may be returned to position to be engaged by said means as said drum revolves.

3. A separating device having in combination, a drum, a magnet carried by said drum in a portion of its periphery, a roller engaging said drum for rotating the same, means for holding said drum stationary with said magnet in operative position and said roller out of contact with said drum, means for rendering said means inoperative, said drum being movable by gravity to cause contact between the same and said roller to cause rotation of said drum.

4. A separating device having in combination, a drum, a magnet carried by said drum in a portion of its periphery, said drum having a flange thereon, a roller engaging said flange for rotating said drum, means for holding said drum stationary with said magnet in operative position, said drum having a recess in said flange which is opposite said roller with the drum in said position.

5. The structure set forth in claim 4, means for rendering said means inoperative to free said drum for rotation, said drum then being movable by gravity to move said recess out of alignment with said roller and cause engagement of said drum and roller to rotate said drum.

6. A separating device having in combination, a revoluble member having a portion of its periphery formed as a magnet, means for delivering material adjacent said member and over said magnet, means for energizing said magnet, means for preventing rotation of said member and means for periodically rendering said last mentioned means inoperative deenergizing said mag-

net and rotating said member through 360 degrees to remove material therefrom.

7. A separating device having in combination, a revoluble drum, a stop, said drum having a portion for engaging said stop and holding said drum stationary, a magnet coil for withdrawing said stop from engagement with said portion, said coil and stop being pivoted for swinging movement, means normally tending to swing said coil and stop and for swinging the same when said stop is disengaged from said portion, a switch movable with said coil in its swinging movement to open the circuit through said magnet coil for permitting said stop to move into position to be again engaged by said portion.

8. A separating device having in combination, a rotatable member having a magnet in a portion of its periphery, means for directing material past said member and magnet, a stop for holding said member in stationary position, a magnet coil for withdrawing said stop, a circuit including said coil and means for periodically closing said circuit to withdraw said stop and permit rotation of said drum.

9. A separating device having in combination, a rotatable member having a magnet in a portion of its periphery, means for directing material past said member and magnet, a stop for holding said member in stationary position, a magnet coil for withdrawing said stop, a circuit including said coil, a timer operated switch for periodically closing said circuit to withdraw said stop, means for rotating said member and means for removing material from said member and magnet.

10. A separating device having in combination, a rotatable member having a magnet in a portion of its periphery, a stop for holding said member in stationary position, a magnet coil for withdrawing said stop, said coil and stop being mounted for swinging movement, a spring normally acting to swing said coil and magnet for swinging the same when said stop is withdrawn, a second member pivoted and adapted to be moved by the swinging of said coil, a switch carried by said second member, a holding magnet for holding said member in the position to which it is moved, said switch acting when said second member is swung to break the circuit through said magnet coil and close a circuit through said holding magnet and means for periodically closing said circuit through said magnet coil.

11. The structure set forth in claim 10, said second member acting as an armature for said holding magnet and being held in the position

to which it is swung by said holding magnet whereby said circuit of said magnet coil is held open.

12. A separating device having in combination, 5 a revoluble member having a portion of its periphery formed as a magnet, means for delivering material along said member adjacent said magnet, a rotating means for said member inoperative when said magnet is in operative position, a stop member for holding said member with said magnet in operative position, periodically operated means for moving said stop member to permit said rotating means to rotate said member through one revolution, means for de- 10 energizing said magnet during said rotation, means for removing material from said magnet and member during said rotation and means for moving said stop to operative position to again hold said member with said magnet in operative 15 position after said rotation.

13. A separating device having in combination, a revoluble member having a portion of its periphery formed as a magnet, means for delivering material along said member adjacent said magnet, a rotating driven means for rotating said member, means for holding said member in stationary position, means for periodically rendering said last mentioned means inoperative to permit said second mentioned means to become operative to rotate said member through 360 degrees, said member then coming to stationary position held by said third mentioned means and means for removing the material from said member and magnet during the rotation of said member.

14. A separating device having in combination, a revoluble member having a portion of its periphery formed as a magnet, means for delivering material along one side of said member adjacent said magnet, rotating driven means constructed and arranged to rotate said member, a stop for holding said member against rotation with said magnet in operative position, means acting periodically for moving said stop to inoperative position to permit rotation of said member 40 through 360 degrees by said second mentioned means, means for deenergizing said magnet during rotation of said member, means for removing material from said magnet and member during rotation of said member and means for moving said stop to operative position to hold said member with said magnet energized and in operative 45 position after said rotation.

FRANK H. JACOBSON.
